DELUSTERED RAYON AND SPINNING
SOLUTION THEREFOR

Frank H. Griffin, Wawa, Pa., assignor to The
Viscose Company, Marcus Hook, Pa., a corpora-
tion of Pennsylvania

No Drawing. Application September 29, 1932,
Serial No. 634,078

2 Claims. (Cl. 106—40)

This invention consists of a process of produc-
ing delustered rayon, and the delustered rayon
so produced.

It has been proposed to deluster rayon yarn
5 by the use of titanium dioxide, but the use of this
delustrant carries the objection that it gives to
the yarn a peculiar shiny appearance. This ap-
pearance may be characterized as metallic, par-
ticularly when such yarn is dyed with the deeper
10 shades. For example, the blues tend to show a
kind of coppery appearance, particularly when
viewed in sunlight at certain angles. This phe-
nomenon has been one of the chief objections to
the use of this method of delustering rayon.

15 I have found that this disadvantage of the
use of titanium dioxide may be eliminated by
the use of a delustrant consisting of the combi-
nation of chlorinated diphenyl with titanium di-
oxide. This chlorinated diphenyl (commercially
20 known as aroclor) is itself a delustrant, and adds
to the delustering effect of the titanium dioxide,
as well as eliminating the peculiar shiny appear-
ance which results from the use of titanium alone.

The amounts may vary between 0.1 to 5.0 per-
25 cent titanium dioxide and between 0.5 to 15.0
percent chlorinated diphenyl. A preferred ex-
ample of yarn produced by my invention is one
containing 0.6 percent titanium dioxide and 4.5
percent chlorinated diphenyl. This preferred ex-
30 ample is as dull as a yarn containing 1.3 percent
titanium dioxide, but does not have its undesir-
able metallic appearance. The percentages given
herein are based on the weight of the cellulosic
content of the viscose solution, or by weight dry
35 yarn. Naturally the proportions might be varied
somewhat in response to the preference of cus-
tomers, but as a rule the amount of aroclor used
will always greatly exceed the amount of tita-
nium dioxide.

40 The required amounts of titanium dioxide and
chlorinated diphenyl in finely divided form, either
separately or together, are distributed through-

out the solution to be spun, prior to the spinning
thereof. The required amount of finely divided
titanium dioxide is thoroughly mixed with a
small amount of water and a dispersing agent,
such as, Turkey red oil. Similarly the required
amount of finely divided solid aroclor is thor-
oughly mixed with water and dispersing agent.
The two delustrants might be prepared together
in a mixed suspension. These suspensions, either
singly or together, are added to the solvent used
to dissolve the cellulose xanthate or preferably
are added to the cellulose xanthate solution just
prior to completion of the solution operation.
The xanthate solution containing delustrants is
then filtered, aged, de-aerated, and spun in the
normal manner. It is, of course, possible to add
the delustrant to the xanthate solution after the
filtering and aging but prior to the spinning.

45 After the titanium dioxide and chlorinated di-
phenyl are incorporated into the solution as de-
scribed above, the solution is spun in the usual
manner.

I claim:—

1. Viscose solution adapted to be spun into de-
lustered rayon yarn and containing from about
50 0.1 to 5.0 per cent titanium dioxide delustrant and
from about 0.5 to 15.0 per cent chlorinated di-
phenyl delustrant, the percentages being based on
the weight of the cellulosic content of the viscose
solution, the amount of chlorinated diphenyl pres-
55 ent being substantially in excess of the amount of
titanium dioxide, and both delustrants being
in the form of finely divided solid particles.

2. As a new article of manufacture, delustered
rayon containing from about 0.1 to 5.0 per cent
60 titanium dioxide delustrant and from about 0.5
to 15.0 per cent chlorinated diphenyl delustrant,
by weight of the dry yarn, the amount of chlori-
nated diphenyl present being substantially in
excess of the amount of titanium dioxide. 65

FRANK H. GRIFFIN.
